[57] **CLAIM**

The ornamental design for a tread element for wheel or
endless track, as shown and described.

DESCRIPTION

FIG. 1 is a top perspective view of a tread element for wheel
or endless track, showing my new design;

FIG. 2 is a bottom perspective view of the tire element
illustrated in FIG. 1;

FIG. 3 is an end elevational view of the tire element
illustrated in FIG. 1;

FIG. 4 is a side elevational view of the tire element illus-
trated in FIG. 1;

FIG. 5 is a reduced bottom plan view thereof; and,

FIG. 6 is a reduced top plan view thereof.
